UNITED STATES PATENT OFFICE.

JESSE M. ARTHUR AND JOHN P. BIRMINGHAM, OF LEXINGTON, VIRGINIA.

COUPLING-PIN LIFTER.

No. 926,636.

Specification of Letters Patent.

Patented June 29, 1909.

Application filed December 23, 1908. Serial No. 468,958.

To all whom it may concern:

Be it known that we, JESSE M. ARTHUR and JOHN P. BIRMINGHAM, citizens of the United States, residing at Lexington, in the county of Rockbridge and State of Virginia, have invented certain new and useful Improvements in Coupling-Pin Lifters; and we do hereby declare the following to be a full, clear, and exact description of the invention, such as will enable others skilled in the art to which it appertains to make and use the same, reference being had to the accompanying drawings, and to the characters of reference marked thereon, which form a part of this specification.

This invention relates to new and useful improvements in gravity pin lifters for car couplers and comprises a simple and efficient device adapted to be raised by the knuckle of the coupler and without direct attachment to the car or draw head and consists of a simple and efficient means whereby the pin may be lifted and the coupler disconnected either by the foot of a person or by hand.

The invention comprises various details of construction, combinations and arrangements of parts which will be hereinafter fully described and then specifically defined in the appended claims.

Our invention is illustrated in the accompanying drawings, in which:—

Figure 1 is an end view of a car showing our improved pin lifting apparatus mounted upon the knuckle of the coupler. Fig. 2 is a sectional view through the car showing in top plan view the coupler and the attachment, and Fig. 3 is an enlarged detail view of the invention.

Reference now being had to the details of the drawings by letter, A designates a car and B a coupler which, in the present instance, is shown of the Janney type and provided with the usual knuckle B'. D designates a bracket member fastened to the car and in which the bracket rod E is positioned and F is a strap or bar fastened at its ends to the lower portion of the car adjacent to one side thereof. Passing through said knuckle is a pin G, and H designates a forked bar having two arms H' and H² which are adapted to straddle said knuckle and each of said arms is provided with an eye N adapted to receive said pin G and hold the bar preferably in the position shown in the drawings. Each of said arms is preferably bent at an angle as at O, as clearly shown in Fig. 2 of the drawings, and

the shank portion of said bar is bifurcated as at K for the reception of the pin lifting lever Q which is pivotally mounted upon a pin R passing through registering apertures in said shank portion. The inner end of said lever or pin lifter is provided with a hook Q' adapted to engage the eye of the coupling pin S in the manner shown clearly in Fig. 1 of the drawings. The handle end of said lever Q is positioned adjacent to one side of the car, the lever being held behind the strap or bar F.

When the parts are adjusted together in the manner shown, it will be noted that a car may be uncoupled conveniently by the brakeman or other person by simply pressing his foot upon the lever, thus leaving his hands free for signaling or other purposes and without danger of injury to life and limb by going between the cars and adjacent to the couplers. As the end of said lever which is connected to the pin overbalances the handle end, the pin will cause the lever to be thrown back to its normal position after the pin has been released.

What we claim to be new is:—

1. In combination with a car and coupler, a coupling pin therein, a bracket member pivotally mounted upon the head of the coupler, a lever pivotally connected to said bracket member and having a hooked end adapted to engage the eye in the coupling pin, as set forth.

2. In combination with a car, a car coupler having a pivoted knuckle and a coupling pin, a bracket member having two arms adapted to straddle the knuckle, means for fastening the bracket member to the coupler; and a lever pivotally connected to said bracket member and engaging said coupling pin, as set forth.

3. In combination with a car, a car coupler having a pivoted knuckle and a coupling pin, a bracket member having two arms terminating each in an eye, a pin pivotally connecting the knuckle to said coupler and passing through said eyes, a lever pivotally mounted upon said bracket arm and connected to said coupling pin, as set forth.

4. In combination with a car, a car coupler having a pivoted knuckle and a coupling pin, a bracket member having two arms terminating each in an eye, a pin pivotally connecting the knuckle to said coupler and passing through said eyes, said bracket member having an upwardly turned slotted shank portion, a pivot pin passing through said

- 2
- slotted portion, a lever pivotally mounted upon said pivot pin and having a hook at one end engaging the eye in the coupling pin, as set forth.
- 5 5. In combination with a car, a car coupler having a pivoted knuckle and a coupling pin, a bracket member having two arms terminating each in an eye, a pin pivotally connecting the knuckle to said coupler and passing through said eyes, said bracket member having an upwardly turned slotted shank portion, a pivot pin passing through said slotted portion, a lever pivotally mounted upon said pivot pin and having a hook at one end en-

gaging the eye in the coupling pin, one end of said lever extending adjacent to the side of the car, and a strap fastened to the car and adapted to guide said lever as it tilts upon its pivot, as set forth.

In testimony whereof we hereunto affix our signatures in the presence of two witnesses.

JESSE M. ARTHUR.
JOHN P. BIRMINGHAM.
